FIRING TRAY FOR DENTAL PROSTHETICS

Allan L. Brent, Dobbs Ferry, and Harvey Bocian, Jericho,
N.Y., assignors to Labco Products, Inc., Jamaica, N.Y.

Filed Sept. 7, 1972, Ser. No. 286,869

Term of patent 14 years

Int. Cl. D24—02, 99

U.S. Cl. D24—1 R

Fig. 7.

Fig. 9.

Fig. 8.

Fig. 10.

Fig. 11.

Fig. 12.

Fig. 13.

Fig. 14.

Fig. 15.Fig. 16.Fig. 17.Fig. 18.

FIG. 1 is a top plan view of a firing tray for dental prosthetics showing our new design;

FIG. 2 is a side elevational view thereof;

FIG. 3 is a top plan view of another embodiment of our design for a firing tray for dental prosthetics;

FIG. 4 is a side elevational view of said embodiment;

FIG. 5 is a top plan view of a further embodiment of our design for a firing tray for dental prosthetics;

FIG. 6 is a side elevational view thereof;

FIG. 7 is a top plan view of another embodiment of our design for a firing tray for dental prosthetics;

FIG. 8 is a side elevational view thereof;

FIG. 9 is a top plan view of yet another embodiment of our design for a firing tray for dental prosthetics;

FIG. 10 is a side elevational view of the embodiment shown in FIG. 9;

FIG. 11 is a top plan view of another embodiment of the firing tray for dental prosthetics;

FIG. 12 is a top plan view of still another embodiment of a firing tray for dental prosthetics;

FIG. 13 is a perspective view of the embodiment disclosed in FIG. 11.

FIG. 14 is a perspective view of the embodiment disclosed in FIG. 12.

FIG. 15 is a perspective view of the embodiment shown in FIGS. 1 and 2;

FIG. 16 is a front perspective view of the embodiment illustrated in FIGS. 3 and 4;

FIG. 17 is a front perspective view of the embodiment illustrated in FIGS. 5 and 6; and

FIG. 18 is a front perspective view of the embodiment illustrated in FIGS. 7 and 8.

We claim:

The ornamental design for a firing tray for dental prosthetics, as shown and described.
